UNITED STATES PATENT OFFICE.

GEORGE W. PRENTICE, OF PROVIDENCE, RHODE ISLAND.

LACING.

No. 920,646.

Specification of Letters Patent.

Patented May 4, 1909.

Application filed May 2, 1906. Serial No. 314,809.

To all whom it may concern:

Be it known that I, GEORGE W. PRENTICE, of Providence, in the county of Providence and State of Rhode Island, have invented 5 certain new and useful Improvements in Lacings; and I do hereby declare the following specification, taken in connection with the accompanying drawings, forming a part of the same, to be a full, clear, and exact 10 description thereof.

The invention relates to lacings for shoes, corsets and the like, and more particularly to the formation of tips in which the stiffener is covered and concealed by the fabric.

15 The invention consists in the employment of a metallic stiffener in the form of a staple, preferably made of wire, and the combination of the same with the fabric of the lacing to form a covered tip.

20 Referring to the drawings, Figure 1 is a perspective view of a tubular lacing embodying my invention; Fig. 2 is a view of the metallic stiffener; Fig. 3 is a plan view of a portion of a lacing with the metallic stiffener 25 inserted within the end of the tubular fabric; Fig. 4 is a view showing the tip partially formed; Fig. 5 is a section on the line $x-x$, Fig. 4; Fig. 6 is a view showing the finished tip.

30 The lacing A shown in the drawing is formed of a tubular fabric, and the metallic stiffener B is in the form of a staple, being preferably formed of wire bent into the shape shown. The stiffener or staple B is inserted 35 within the end of the tubular fabric, as shown in Fig. 3. One side of the fabric is then tucked down between the legs of the staple and the fabric and staple are then 40 squeezed together laterally by means of suitable dies or otherwise, and thereby put into the form shown in Figs. 4 and 5. As the fabric employed for these lacings is a braided fabric, the fabric when severed will be more or less frayed at the end with the loose ends 45 of the threads or fibers projecting from the body of the fabric, as shown in Fig. 4. The tip in this form is then dipped in glue or other suitable adhesive material. If desired, the tip may be then subjected directly 50 to the action of the finishing dies and the action of such dies relied upon to close together the frayed ends of the threads and form the finished end of the tip. It is pre-

ferred, however, before subjecting the tip to the action of the finishing dies to draw down 55 the frayed ends of the threads with the fingers or otherwise and then subject the tip to the action of the finishing dies which operate to still further reduce the diameter of the tip and put it into the finished form shown in 60 Fig. 6. In either case the frayed ends when compacted together, either by the fingers and the action of the finishing dies or by the action of the finishing dies alone, will be held in this compacted condition by the glue or 65 other adhesive material. Preferably the finishing dies are constructed to form the tips with a tapering or more or less rounded end as shown.

As will be understood, the glue or other 70 adhesive material not only serves to hold the frayed ends in compacted condition, but also serves to stiffen the tip and to assist in holding the metallic stiffener or staple in place and adds to the finish and durability 75 of the tip.

Flat lacings may likewise be provided with similar tips constructed in substantially the same manner, except that in such case the metallic stiffener or staple, instead of being 80 inserted within the end of a tubular fabric, is placed upon the flat fabric and the edges of the fabric folded over and tucked down between the legs of the staple.

What I claim as my invention and desire 85 to secure by Letters Patent is:

1. A lacing-tip comprising a fabric and a staple incased within the fabric, said staple and fabric being compressed transversely to form the lacing-tip, substantially as de- 90 scribed.

2. A lacing-tip comprising a tubular fabric and a staple inserted within the tubular fabric, said staple and fabric being compressed transversely to form the lacing-tip, 95 substantially as described.

3. A lacing-tip comprising a fabric and a staple incased within the fabric, said staple and fabric being compressed transversely, and the end of the fabric being held com- 100 pacted by suitable adhesive material to form the finished tip, substantially as described.

GEORGE W. PRENTICE.
